UNITED STATES PATENT OFFICE

HARRY A. WINTERMUTE, OF PLAINFIELD, NEW JERSEY, ASSIGNOR TO RESEARCH CORPORATION, OF NEW YORK, N. Y., A CORPORATION OF NEW YORK

ELECTRICAL PRECIPITATOR

Application filed June 15, 1931. Serial No. 544,569.

This invention relates to electrical precipitators for the removal of suspended particles from gases and especially to that type of precipitator which is divided into a plurality of 5 horizontal gas passages by extended vertical surfaces which function as collecting electrodes. Its scope may be further defined in that it relates in particular to electrical precipitators intended for the collection of dry 10 comminuted material which requires baffles or pockets on the surfaces of the collecting electrodes to prevent creepage of the deposited material along these surfaces.

Objects of the present invention are to 15 provide a simple and economical collector electrode assembly which possesses sufficient rigidity to remain properly aligned in the precipitator, which presents transverse pockets 20 or other interruptions at the collecting surface to prevent material that is not definitely held to the surface from moving along the electrode and reentering the gas stream, which does not offer a high resistance to the 25 passage of gas through the precipitator, and which presents a satisfactory terminating surface for the electric field. A further object is to provide a collector electrode assembly which may be effectively vibrated or 30 shaken by known rapping devices to shake off collected material which tends to adhere to the electrode and build up beyond a permissible depth. A further object is to provide an electrical precipitator in which collecting 35 electrodes of the type stated and the discharge electrodes are so arranged as to result in distinct advantages over previously used and/or suggested constructions. More specifically, an object is to provide a collector 40 electrode assembly in which a plurality of channel members, preferably of identical form, are arranged with the flanges of adjacent channels projecting in opposite directions and with the channel webs arranged 45 in two parallel planes.

These and other objects of the invention will be apparent from the following specification, when taken with the accompanying drawings, in which:

50 Fig. 1 is a plan view of a precipitator con-

structed according to the invention, with a portion of the top wall broken away,

Fig. 2 is a side elevation view with parts shown in section as taken on line 2-2 of Fig. 1,

Fig. 3 is a vertical section taken on line 3-3 of Fig. 2,

Figs. 4, 5 and 6 are fragmentary side, plan and end views, respectively, of a portion of the collecting electrode,

Fig. 7 is a somewhat diagrammatic plan view showing arrangements of the electrodes in the precipitator, and

Figs. 8 and 9 are similar diagrammatic views of other forms of collector electrode structures embodying the invention.

In Figs. 1, 2 and 3, which illustrate the invention as embodied in one known form of precipitator, the reference numeral 1 identifies the casing of the precipitator, which casing is supported by uprights 2 and has an inlet flue 3, an outlet flue 4, and hoppers 5 for the collection of the material.

An insulator housing 6 on the top wall of the casing 1 houses a pair of insulators 7 supporting a cross member 8 to which is electrically connected a conductor 9 which passes out of the housing through an insulating bushing 10 and is connected to a source (not shown) of high potential current, preferably unidirectional current. The circuit is completed by a ground connection attached to the housing. Depending from the cross member 8 is a vertical member 11 which extends through an opening in the top wall of the casing and carries a supporting frame 12 from which are suspended a plurality of discharge electrodes 13 arranged in rows extending longitudinally of the chamber. A spacing frame 14 secured to the lower ends of the electrodes serves to maintain the electrodes in proper spaced relation.

The opening between the casing 1 and the housing 6 is closed by an annular insulator 15 of comparatively flexible, heat resisting, insulating material, such as asbestos cloth, which is secured at its outer diameter to the top wall of the housing and at its inner diameter to the vertical member. The insulator is shown as arranged with a portion pro-

jecting into the chamber so as to lie in the path of the gas. Such an arrangement is employed where the gas passing through the precipitator is hot and dry and/or the suspended material is insulating in character, thus the insulator is heated by the gas and no condensation of suspended gaseous material occurs. Where the gas which is treated is normally below the dew point and/or the suspended material is of a conducting nature, the insulator is located out of the gas stream so that the gas does not readily encounter the insulator.

Extending across each end of the chamber is a pair of vertically spaced supporting members 16 which carry two sets of vertically aligned collector electrodes 17 that extend through the casing 1 to subdivide the space within the casing into a plurality of relatively narrow gas passages. As shown in Fig. 1, each collector electrode is not flat but includes flat or plane sections which lie in two different vertical planes, thus giving the effect of a plate having flat corrugations that are relatively wide and shallow.

A plurality of rapping devices 18, which may be vibrators operated by air pressure, steam or electrical means, are mounted on the casing 1 and include rods 19 which extend through the casing and into engagement with the collector electrodes.

As shown in Figs. 4, 5 and 6, the collector electrodes 17 are not formed by corrugating an elongated metal plate but are built up from a plurality of channel members which are secured to the reversely bent members 20, 21; the ends of the upper member 20 being projected somewhat beyond those of the lower member 21 to engage the supporting members 16. The webs 22 of the channel members lie in two spaced parallel planes and the flanges 23 of the channels preferably do not contact with each other but, as shown in Fig. 6, engage opposite faces of the short transverse sections of the members 21, 22. The securing means, such as rivets 24, which fasten the channels to the members 20, 21 pass through the channel webs and thus lie outside of the main gas stream between adjacent collector electrodes.

The shaker rods 19 pass through the lower edges of the channels and member 21 and are fixed to the member 21 by nuts 25. As the channels are secured only at their upper and lower edges, and are relatively long, it will be apparent that each channel will respond readily to jarring and shaking movements transmitted from the rapping devices 18 by the rods 19.

Referring to Fig. 7, which shows portions of two electrodes 17 defining a gas passage and the position of the discharge electrodes 13 in said gas passage, it is noticed that the discharge distance "a" is appreciably less than discharge distance "c". The strongest

electric field will be, of course, from the discharge electrode 13a to the back of the channel web 22a to give a discharge distance "a". The velocity of the gases here will also be at a maximum and there will be a tendency for the flowing gas to carry off any dust which does not stay attached to the web 22 at this portion of the gas passage. Particles leaving this part of the passage, however, continue to find themselves in a comparatively strong electric field when they pass between discharge electrode 13b and the open side of the next channel 22b.

The relative dimensions of the pockets formed by the channel members are important if the collector electrodes are to function at high efficiency and positively retain material which is swept out of the narrow portions of the gas passage and into the wider spaces where the open sides of the channels 22b oppose each other. While the optimum dimensions may vary somewhat with different installations, the channel depth should, in general, be at least one inch and preferably about two inches, that is, distance *c* should exceed the distance *a* by at least one inch. The breadth *b* of the pockets is also important and, in general, it will be found that a channel width of between about 12 and 24 inches will give satisfactory results. The spacing, *d*, of the discharge electrodes 13 should be at least equal to the minimum spacing *a* between the two sets of electrodes but the exact spacing for optimum results will depend upon the particular installation and the gases to be treated.

The dimensions dictated by the electrical requirements are quite satisfactory from a mechanical standpoint. Channel members of about four feet in length may be of relatively light weight as the flanges 23 will reinforce the webs 22, thus providing sufficient stiffness even though the channels are formed of relatively thin metal sheets.

As shown in Fig. 8, partially closed pockets may be provided at the edges of the channels away from the incoming gas stream by flanges 26 which project from the webs 22' and across a part of the trailing edge of the preceding pocket.

A similar arrangement is shown in Fig. 9 in which one flange 27 of each plate is bent over to provide a short section parallel to the web 28 of the channel. To secure a relatively uniform field throughout the gas passage, tubes or bars 29 are placed across the opening of the channel to provide a terminating surface for the electric field in this region. While the electric field terminates to a large extent on these bars, the moving material which leaves the back of an adjacent channel member can pass around the bars to enter the pocket behind them.

The invention provides a simple, light and relatively inexpensive construction in which

a plurality of rectangular shaped pockets are provided for trapping material that tends to slide along the face of the collecting electrodes, the material being retained in the pockets until, either by its own weight or due to rapping, it drops down the surface of the pocket and into the collecting hoppers. There is but little tendency for the dust to sneak out of the rectangular shaped pockets and this tendency may be reduced by employing the types of channel shown in Figs. 8 and 9. The resistance to gas flow is not materially increased by the construction, particularly when the pockets are not close together and the changes in gas velocity are neither abrupt nor frequent.

It is to be understood that the invention is not limited to the particular arrangements which have been described as various changes may be made in the parts and in their relative size, shape and relationship without departing from the spirit of the invention as set forth in the following claims.

I claim:

25 1. In an electrical precipitator, the combination with a casing defining a gas chamber, of a plurality of collecting electrodes disposed in spaced, parallel alignment to define a plurality of gas passages in said chamber, and discharge electrodes in said passages, each of said collecting electrodes comprising a plurality of members having longitudinal stiffening flanges, said members being disposed in alignment with their flanges adjacent one another and with the similar faces of adjacent members facing in opposite directions.

2. The invention as set forth in claim 1, wherein the flanged members of the two collecting electrodes which cooperate to define a gas passage are transversely aligned, and the concave sides of flanged members of one electrode are opposite the concave sides of the flanged members of the other electrode.

45 3. In an electrical precipitator, a collector electrode comprising a pair of reversely bent members having relatively long, flat sides arranged alternately in two parallel planes and joined by short transverse sections, and channel members arranged with ends of the webs thereof engaging the flat sides of side members and with the webs thereof engaging the said short transverse sections, means passed through channel members and said reversely bent members to connect said members to each other.

4. The invention as set forth in claim 3, wherein the opposed flanges of adjacent channel members engage opposite sides of the transverse sections of said reversely bent members, thereby to space adjacent flanges from each other.

5. The invention as set forth in claim 3, wherein said connecting means are located only at the flanges of said channel members.

6. In an electrical precipitator, the combination with a gas chamber, and discharge electrodes therein, of a collector electrode comprising a supporting member and vertically disposed members carried by said supporting member to provide a substantially continuous collector surface extending in the direction of gas flow through said chamber, one of said vertically disposed members comprising a channel having web and flange elements, the web of said channel being offset from the plane of the adjacent portions of the collector electrode to form a vertically disposed pocket. 70

7. The invention as set forth in claim 6, in combination with means extending parallel to and spaced from said channel web to partially close said pocket. 80

8. The invention as set forth in claim 6, in combination with spaced conducting means extending across said pocket and in the plane of the said adjacent portions of the collector electrode. 85

9. In an electrical precipitator, the combination with a casing providing a gas chamber, of a plurality of collector electrodes defining gas passages in said chamber and discharge electrodes in said gas passage, each of said collecting electrodes comprising a plurality of aligned channel members and means partially closing the channels. 90

10. The invention as set forth in claim 9, wherein said means comprises a projecting portion on each of said channel members arranged to overlie the channel. 100

11. The invention as set forth in claim 9, wherein said means comprises a projecting portion on each of said channel members extending from a flange thereof and parallel to the web of the channel member. 105

12. The invention as set forth in claim 9, wherein said means includes a plurality of bars arranged in alignment across the opening of each of said channels and extending parallel to the web of the channel. 110

13. The invention as set forth in claim 9, wherein said means includes a portion projecting from the web of each of said channel members and arranged to overlie the channel of an adjacent channel member. 115

14. An electrode for electrical precipitators comprising a plurality of vertically disposed channel members arranged side by side to constitute a substantially continuous surface, and means for connecting said channel members including members secured to the ends only of said channel members, and lying flat against the surfaces of at least some of said channel members. 120

15. In an electrical precipitator, the combination with collector electrodes defining a gas passage and each having portions of the collecting surface arranged in different parallel planes extending along said gas passage, of a series of discharge electrodes in 130

said gas passage and cooperating with said collector electrode, at least one discharge electrode being positioned opposite each of said portions of said collecting surface.

- 5 16. In an electrical precipitator, a pair of collector electrodes having substantially continuous opposed surfaces defining a gas passage, the opposed surfaces of said electrodes being symmetrically disposed at opposite 10 sides of the medial plane of said passage and including portions lying at different distances from said medial plane, whereby the gas passage includes zones whose transverse width is greater than that of other zones, 15 and discharge electrodes in said gas passage and between those opposed surfaces of said collector electrodes which define a narrow zone.

17. The invention as set forth in claim 16, 20 in combination with discharge electrodes arranged in said gas passage at the wider zones thereof.

18. In an electrical precipitator, in combination, a collecting electrode comprising a 25 plurality of composite collecting elements disposed substantially parallel and defining a gas passage, each of said composite elements including a plurality of rectilineally grooved members extending transversely to 30 the direction of gas flow in the passage, and a plurality of discharge electrodes in said passage, at least one of such discharge electrodes in said passage being disposed opposite each of said grooved members.

- 35 19. In an electrical precipitator, a collector electrode comprising a supporting member, and a plurality of channel members secured to said supporting member with the open sides of adjacent channels faced in 40 opposite directions, the flanges of each channel member lying within the open space of the respective adjacent channel member, and being spaced from the flanges thereof.

In testimony whereof, I affix my signature.
45 HARRY A. WINTERMUTE.
